UNITED STATES PATENT OFFICE.

KINTARO MIYAKAWA, OF SAN FRANCISCO, CALIFORNIA.

SHOE-FASTENER.

1,378,602.

Specification of Letters Patent. Patented May 17, 1921.

Application filed September 10, 1919. Serial No. 322,945.

To all whom it may concern:

Be it known that I, KINTARO MIYAKAWA, a subject of the Emperor of Japan, residing at the city and county of San Francisco and 5 State of California, have invented new and useful Improvements in Shoe-Fasteners, of which the following is a specification.

This invention relates to shoes and particularly pertains to a fastener therefor. It 10 is the principal object of the present invention to provide a fastener for lace shoes which will have the appearance of a shoe lace as it is carried from one eyelet of the shoe to the other and which may be easily 15 mounted in a fastening position upon the shoe to serve the purpose of the usual fabric lace.

The present invention contemplates the use of a tubular metal fastener of a length 20 substantially agreeing with the distance between complementary eyelets of a shoe and being fitted with yieldably supported pins adapted to seat within said eyelets to hold the fastener in position and thereby bind 25 the two sides of the upper part of the shoe together.

The invention is illustrated by way of example in the accompanying drawings, in which—

30 Figure 1 is a view in perspective, illustrating a shoe fitted with the present invention.

Fig. 2 is a view in elevation, showing the appearance of the normally exposed part of 35 the fastener.

Fig. 3 is a view in elevation, showing the appearance of the under-side of the fastener.

Fig. 4 is an enlarged view in longitudinal section through the fastener on the lines 40 4—4 of Fig. 2, illustrating it as applied to a shoe upper.

Fig. 5 is an enlarged fragmentary view of the central portion of the fastener, showing the intermediate connection of the 45 spring.

Fig. 6 is an enlarged view in section through one of the fastening buttons, as seen on the line 6—6 of Fig. 4.

Fig. 7 is a vertical section on line 7—7 of 50 Fig. 8.

Fig. 8 is a horizontal section on line 8—8 of Fig. 7, showing a modified form of the eyelet.

In the drawings, 10 and 11 indicate the 55 two flaps of a shoe upper. These flaps are

fitted along their adjacent marginal edges with a plurality of eyelets 12. The eyelets are provided as sockets for male fastening members 13, which may be of the glove fastener type and which are yieldably secured 60 within the eyelets, either by the use of a yieldable member incorporated within the eyelet or weakened portions in the fastener 13, whereby it may be slipped into place and held in frictional engagement with the eyelet. Fastening members 13 are mounted upon enlarged head portions 14 which are intended to seat within a channel-shaped passageway 15 of a combined guide and body member 16. These body members are 70 preferably formed of thin metal which have been japanned or otherwise colored to agree with the color of the shoe. The length of these members is slightly greater than the over-all distance between the complementary eyelets upon the two shoe flaps, clearly shown in Fig. 4. Thus it will be seen that the body member 16 will conform to the instep of the shoe when the male fastening members 13 are seated within the eyelets 12. 80

In order that the male fasteners may be yieldably supported in position, they are secured to the opposite ends of a spring 17. This spring is fixed to the body portion 16 by a central pin 18. 85

In operation of the present invention a plurality of fasteners are provided, agreeing with the number of sets of eyelets on the shoe. In the present instance six are used. These fasteners are of varying length so that 90 the shoe uppers will be held in proper relation to each other to conform to the contour of the foot. The fasteners are then placed in position by first inserting one of the male fastening members 13 into an eyelet and 95 thereafter drawing the member across the shoe while stretching the spring 17 until the other male fastening member is in register with the corresponding eyelet upon the opposite flap of the upper. When this result 100 has been attained, the fastener will conform to the contour of the shoe and hold the flaps of the upper in yieldable relation to each other.

It will thus be seen that the device here 105 disclosed, while simple in construction, will afford a permanent and desirable substitute for shoe laces and at the same time will be of such a simple and inexpensive construction as to have commercial value. 110

While I have shown the preferred form of my invention, various changes in the construction and arrangement of the several parts herein shown and described may be 5 resorted to without departing from the spirit of my invention as disclosed in the appended claims.

Having thus described my invention, what I claim and desire to secure by Letters Patent is—

1. A fastener for lace shoes, comprising a body member arcuated in shape and greater in length than the distance from one eyelet of the shoe to a complementary eyelet, a 15 pair of buttons slidably carried by said member, and means yieldably connecting said buttons with said body member.

2. A fastener for lace shoes comprising a rigid arcuate body member, a pair of buttons 20 slidably carried thereby, and means

yieldably connecting said buttons with the body member.

3. A fastener for lace shoes comprising an arcuate, rigid body member of channel section, a pair of male fastening members 25 slidable within said channel, a central pin fastened to the body member, a spring secured intermediate its ends to the pin and by its opposite ends to the fastening members, whereby said fastening members may 30 be yieldably held in relation to each other when positioned within eyelets upon a shoe.

In testimony whereof I have hereunto set my hand in the presence of two subscribing witnesses.

KINTARO MIYAKAWA.
